UNITED STATES PATENT OFFICE

2,126,702

SADIRON

Edward K. Jamieson, Toronto, Ontario, Canada

Application July 1, 1937, Serial No. 151,337
Renewed June 23, 1938

3 Claims. (Cl. 158—23.2)

The invention appertains to a sadiron heated by an alcohol burner and has for its general object to produce an improved heating unit that not only is simple of construction but also is economical of operation.

More particularly the invention aims to provide a safe and reliable generator and burner tube combined as a unit with the fuel storage tank. The parts are so associated that they are detachably mounted as a unit in the body of the sadiron.

A distinctive feature lies in the mode of mounting the unitary members and securing them in a detachable manner.

The invention will be better understood by reference to the accompanying drawing in which Figure 1 is a side elevation of the sadiron.

Figure 2 is a rear elevation viewed on the line 2—2 looking in the direction of the arrows and depicting a locking plate in open position.

Figure 3 is a similar view but showing the locking plate in closed position.

Figure 4 is a lengthwise sectional view of the heating unit removed from the body.

Figure 5 is a fragmentary rear perspective view of the body showing a slot that forms part of the mounting for the heating unit.

Like numerals of reference indicate corresponding parts in each figure throughout the drawing.

In the embodiment of the invention herein illustrated, the body 6 is of conventional shape, having a suitable handle 7 and the customary complement of passages 8 for admitting air and for allowing escape of the products of combustion.

The interior of the body constitutes a heating chamber 9.

The burner tube 10 extends forwardly from the rear of the body and is perforated at each side to provide longitudinal series of holes as at 11 for the flame jets.

The rear of the burner tube has a crook 12 from which the tube is upwardly continued at 13 and joined by a coupling nut 14 to the valve 15, there being one or more vent openings 16 below the nut 45 to admit air so as to form a combustible mixture forwardly of the valve.

The valve has a passage 17 communicating with a generating chamber 18 and controlled by the needle valve 19 that upwardly extends from the top of the valve. A horizontal wick tube extends rearwardly from the valve and is connected by a coupling nut 20 to the fuel tank 21. The wick 22 extends into the tank to draw up the liquid fuel and to convey it to the generating chamber.

To start the burner in operation, external heat is applied by a pilot or other known means to vaporize the volatile fuel in the generating chamber. The gas flows down the burner tube, commingles with air admitted by the perforated part 5 13 and burns in jets emanating from the holes 11.

The burner tube, valve and tank are referred to as a unitary heating unit. The mode of detachably mounting this unit in the body comprises the provision of the slot 23 extending inwardly from the top of the rear face 24 of the body. The valve is supplied with a pair of spaced flanges 25 at each side so as to define respective intervening recesses. The recessed portion of the valve is inserted in the slot 23 so that the flanges shoulder 15 it on the body and thus mount the heating unit in proper position.

To secure the heating unit in position, a locking plate 26 is employed, which plate is disposed adjoining the rear face 24 and pivoted at 25 to 20 one side of the body for swinging movement in a transverse plane, for which purpose a knob 26' is supplied. The locking plate rests on a shoulder 27 and has an arcuate slot 28 extending upwardly from its bottom edge and curved substantially on a radius whose centre is coincident with the pivot 25 so as to clear the wick tube. The plate blocks the valve in its closed position. The locking plate carries a closure plate 29 pivoted at 30 and adapted to lie across the slot 28. Said closure 30 plate has vent passages 31.

What I claim is:

1. In a sadiron, an elongated chambered body open at the rear end, said rear end terminating abruptly in an end face, said rear end including 35 a top wall having a slot extending inwardly from said end face, a unitary heating unit including a valve having a horizontal tube extending therefrom, said valve having a pair of spaced flanges on each side defining recesses by which the valve 40 is inserted in the aforesaid slot, and a locking plate pivoted to the end face aforesaid and adapted to transversely swing over the horizontal tube to retain the valve in place, said locking plate having an arcuate slot receptive to the horizontal tube.

2. In a sadiron, an elongated chambered body open at the rear end, said rear end terminating abruptly in an end face, said rear end including a top wall having a slot extending inwardly from 50 said end face, a unitary heating unit including a valve having a pair of spaced flanges on each side defining recesses by which the valve is inserted in the aforesaid slot, and a locking plate pivoted to the end face aforesaid so as to swing into en- 55

gagement with the valve to retain it in the slot.

3. In a sadiron, an elongated chambered body open at the rear end, said rear end terminating abruptly in an end face, said rear end including a top wall having a slot extending inwardly from said end face, a unitary heating unit including a valve having a pair of spaced flanges on each

side defining recesses by which the valve is inserted in the aforesaid slot, and a locking plate pivoted to the body laterally of the valve, said locking plate having an arcuate slotted portion adapted to fit over the valve to retain it against displacement.

EDWARD K. JAMIESON
